UNITED STATES PATENT OFFICE.

WILLIAM H. STEBBINS, JR., OF BUFFALO, NEW YORK.

TROLLEY-RESTORER.

984,712.

Specification of Letters Patent. Patented Feb. 21, 1911.

Application filed January 14, 1910. Serial No. 537,999.

To all whom it may concern:

Be it known that I, WILLIAM H. STEBBINS, Jr., a citizen of the United States, residing at Buffalo, in the county of Erie and State of New York, have invented a certain new and useful Improvement in Trolley-Restorers, of which the following is a full, clear, concise, and exact description.

My invention relates to an automatic trolley-restoring device, and its object is to provide mechanism of simple construction which can readily be used in connection with the ordinary trolley-pole and which will automatically restore the trolley into running contact with its wire in case it should accidentally escape therefrom.

My invention consists of a trolley-restoring member mounted upon the trolley-pole near the upper end thereof and adapted to be projected in an upward position to bring the trolley-wire above the trolley-wheel, and automatically operated mechanism for controlling the operation of said restoring member, said mechanism being arranged to be set in motion mechanically upon the escape of the trolley from the wire, and thereby to replace the trolley in contact with the wire and reset the trolley-restoring device.

In its preferred embodiment my invention consists, more specifically stated, of a trolley-restoring member having arms extending upon the opposite sides of the trolley-wheel and pivotally carried upon the upper end of the trolley-pole, a piston having a rod and lever connection with said restoring member, a chamber in which said piston reciprocates, a valve controlling the admission of compressed air from an air-brake system, said valve being so arranged as to be mechanically operated, upon the escape of the trolley from the wire, to admit compressed air to the cylinder and thereby to reciprocate said piston, which in turn operates the trolley-restoring member and resets the entire mechanism in its initial normal condition.

My invention may be more readily understood by reference to the accompanying drawings, in which,

Figure 1 is a side elevation, with parts broken away, of a trolley-pole equipped with my invention; Fig. 2 is a plan view showing the trolley-restoring member and the operating lever thereof detached from the trolley-pole, said figure also showing the normal relative position of the arms of the restoring

member with respect to the trolley-wheel; Figs. 3 and 4 are longitudinal central sectional and end views, respectively, of the piston and cylinder which controls the operation of the restoring fork.

Similar letters of reference refer to similar parts throughout the several views.

My invention is adapted to be used in connection with an ordinary trolley-pole 1, provided at its upper end with the trolley-wheel 2 mounted in the harp 3 and spring-pressed in the usual manner (not shown) into running contact with the trolley-wire 4. Clamped or otherwise suitably secured to the pole 1 below the harp 3 is a bracket 5. The arms 6, 6 of the trolley-restoring member are provided at their lower ends with alined openings 7 through which they are pivoted to the bracket 5 as shown in Fig. 1. The upper ends of the arms 6, 6 have secured thereto a trolley engaging device which preferably consists of a metallic bar or fork having a central groove or depression 8 and oppositely and upwardly extending arms 9, 9. The groove 8 lies below the trolley-wire 4 and always remains in alignment with the usual groove in the trolley-wheel. The two arms 9, 9 extend upon the opposite side of the trolley-wheel 2, so as to engage the wire 4 in case the trolley escapes therefrom.

The bell-crank lever 10 is pivoted at its apex 11 to the bracket 5 above the pivot point 7 of the arm 6, 6. The short arm 12 of the bell-crank lever is slotted to receive the cross-bar 13 which connects the arms 6, 6. The depression of the long arm 14 of the bell-crank lever will thus elevate the arms 6, 6 and the trolley engaging member 95 engaged thereby.

The outer end of the arm 14 of the bell-crank lever 10 has pivoted thereto an operating rod 15, the lower end of said rod being connected by the coupling nut 16 with the plunger or piston rod 17. Secured upon the rod 17 is the piston head 18, which is mounted to reciprocate in the piston chamber or cylinder 19, said cylinder being closed at its upper end 20 and open at its lower end 21. The cylinder 19 is provided near its lower end with three ports, 22, 23, 24. The port 22 communicates with the pipe 25 of the usual air-brake system of the car upon which the trolley-pole is mounted. The port 24 communicates through a pipe 26 with the port 27, which opens into the upper end of

the cylinder 19. Intermediate the ports 22 and 24 is the exhaust port 23. The ports 22, 23 and 24 are controlled by a reciprocating valve 28 which is preferably in the form of a short hollow cylinder fitting within the cylinder 19 and open at each end in order to prevent any accumulation of air pressure between said valve 28 and the piston 18. The lower end of the cylinder 19 thus constitutes a valve chamber for the sliding valve 28. The valve 28 has a thickened portion 29 provided with a valve passage 30 so arranged that in one position of said valve 28 the ports 23 and 24 are connected, as shown in Fig. 3, while in the other position thereof, the ports 22 and 24 are connected. The port 24 is thus always in communication with the valve passage 30, and hence the connection of the upper end 20 of the piston 19 with the air-brake system or with exhaust is dependent upon the position of the valve 28.

The upper end of the valve 28 is provided with a flange 31 adapted to be engaged by a collar 32 upon the lower end of the piston rod 17, the piston thus by an initial limited upward movement operating the valve 28 so as to bring the port 22 into communication with the valve chamber 30. Another collar 33, likewise carried by the piston rod 17 on the underside of the piston 18, serves to restore the piston valve 28 to its initial position, as will hereinafter be more fully described. The piston head 18 is provided with a sleeve 34, and surrounding said sleeve between piston 18 and the cylinder head 20 is a coiled spring 35. The sleeve 34 is of such length as to admit of a slight initial upward movement of the piston 18 from the position shown in Fig. 3, in order that a similar limited movement may be transmitted through the nut 32 to the piston valve 28, as hereinafter described. The extent of the downward movement of the piston 18 is determined by a collar 36 carried by the rod 17 above the cylinder head 20, said collar 36 abutting against the cylinder head to stop the downward movement of the piston rod and piston. The coiled spring 37 surrounds the upper end of the piston rod 17 between the cylinder head 20 and the nut 16.

The operation of the trolley-restoring device is as follows: Assume that the trolley is in the normal running position shown in Fig. 1, in which case the trolley-restoring device will likewise be in its normal position as shown. It will be understood that the trolley-pole 1 is of the usual construction. In the event therefore of the wheel 2 escaping from the wire 4, the trolley-pole 1 will fly upward, in the usual manner. This will bring one or the other of the arms 9, 9 of the trolley-restoring fork into engagement with the wire 4 and the pressure there-

of against said wire will cause the arms 6, 6 to swing out from the wheel 2 upon their pivotal points 7, thus operating the bell-crank lever 10 to pull the rod 15 in an upward direction. The upward pull on the rod 15 is communicated to the piston rod 17, and the nut 32 upon the lower end thereof engages with the flange 31 of the valve 28 and raises said valve so that the port 22 is brought into communication with the port 24 through the valve chamber 30, and the exhaust port 23 is closed. Compressed air from the air-brake system thus is admitted into the upper portion of the cylinder 19 through the port 27, and the piston 18 is thereupon forced in the opposite or downward direction, thereby giving a downward pull upon the rod 15, which, in turn, operates the bell-crank lever 10 to throw the arms 6, 6 and the arms 9, 9 carried thereby in an upward direction against the force presented by the trolley-wire. In this position the arms 6, 6 will straddle the wheel 2 and the arms 9, 9 will be slightly elevated above the trolley-wheel. The wire 4 will thereupon move down into the central groove 8. At the extreme downward movement of the piston 18, the extent of which, as has heretofore been stated, is determined by the collar 36, the collar 33 engages with the flange 31 of the valve 28 and moves said valve to its initial position shown in Fig. 3. The air inlet 22 is thus closed and the cylinder chamber above the piston head 18 is connected with the exhaust port 23. The coiled spring 37 thereupon expands and moves the piston 18 upwardly, the cylinder meanwhile exhausting through ports 27, 24 and 23. The coiled spring 34 acts as a bumper to stop the upward movement of the piston rod before the collar 32 can engage with the flange 31 of the valve 28. The upward movement of the piston rod 17 will, through the rod 15 and lever 10, lower the arms 6, 6 and the trolley-restoring fork carried thereby, and since the trolley-wire is held in the groove 8, it will be brought into the aligned groove of the trolley-wheel, as will be readily understood. The trolley-wheel is thus restored into running position, and the several parts of the restoring device are reset to their normal positions.

It will thus be understood that the valve 28 acts as a movable controller for bringing into action the operating mechanism which actuates the trolley-restoring member, said operating mechanism consisting preferably of the piston 18 and cylinder 19 operated from the air-brake system and connected by a system of levers 15, 10 with the arms 6, 6 of the trolley-restoring member. The movable controller or valve 28 is loosely connected to the piston rod 17 preferably by means of the nuts 32 and 33 which lie upon the opposite sides of the flange 31 of said

valve. It is evident, however, that the plunger rod can be arranged to be operated from any convenient source of power and that the movable controller can be modified accordingly, all within the broad scope of my invention.

What I claim is:—

1. The combination with a trolley-restoring member; of a piston rod operatively connected therewith and arranged to be given an initial limited movement by downward pressure exerted on said restoring member; a cylinder; a piston secured to said piston rod and fitting in said cylinder; 15 a valve chamber provided with a port for the admission of compressed air, a port communicating with the piston chamber and an exhaust port; and a valve operatively connected to said piston rod and controlling said ports of said valve chamber.
2. The combination with a trolley-restoring member; of a piston rod operatively connected therewith and arranged to be given an initial limited movement by downward pressure exerted on said restoring member; a cylinder having a closed upper end and an open lower end; a piston fitting in the upper end of said cylinder and secured to said piston rod, the lower end of the 25 said cylinder being provided with a port for the admission of compressed air, a port communicating with the piston chamber and an exhaust port; and a cylindrical valve slidably mounted in the lower end of said cylinder and slidably connected to said piston rod, said valve in one position connecting the compressed air port with the port to the piston chamber and in its opposite position connecting the port to the piston chamber 30 with the exhaust port.
3. In a trolley-restoring device, the combination with a trolley-pole and a trolley carried thereby for engagement with a feed wire; of a trolley-restoring member comprising arms pivoted at their lower ends to said pole and provided at their upper ends with a fork having a central groove and arms extending therefrom upon the opposite side of the trolley; a bell-crank lever 35 pivoted at its apex and at one end thereof to said pole and said arms of the restoring member, respectively; a plunger rod having an upward extension pivotally connected to the other end of said bell-crank lever; operating means for reciprocating said plunger rod; and a movable controller for said operating means actuated from said plunger rod and arranged to be moved into operative position by the pressure of said restoring 40 member against said wire.
4. The combination with a trolley-restoring member, of an operating rod connected therewith and arranged to be given an initial limited movement in one direction by downward pressure exerted on said restor-

ing member, a piston arranged to be actuated by air-pressure for operating the rod in the opposite direction, and a valve controlling the air-pressure upon said piston, said valve being slidably connected to said operating rod and arranged to be opened by said initial limited movement of the operating rod and to be closed upon the completion of the stroke of the piston in the opposite direction, whereby said rod and piston have a limited longitudinal movement without any corresponding movement of said valve.

5. In a trolley-restoring device, the combination with a trolley-pole and a trolley carried thereby for engagement with a feed wire; of a movable trolley-restoring member mounted on said pole and lying underneath said wire in position to be projected against the same upon the escape of said trolley 85 from the wire, a piston rod operatively connected to said restoring member and arranged to be given an initial limited movement by downward pressure exerted by said wire upon said restoring member, a cylinder, 90 a piston fitting therein and carried by said piston rod, and a sliding valve controlling the admission of compressed air to said cylinder, said valve being slidably connected to said operating rod and arranged to be 95 opened by said initial limited movement of the operating rod and to be closed upon the completion of the stroke of the piston in the opposite direction, whereby said rod and piston have a limited longitudinal movement without any corresponding movement 100 of said valve.

6. The combination with a trolley-restoring member; of a piston rod operatively connected therewith and arranged to be given an initial limited movement by downward pressure exerted on said restoring member; a cylinder having a closed upper end and an open lower end; a piston fitting in said cylinder and secured to said piston rod intermediate the ends thereof; a cylindrical valve slidably mounted in the lower end of said cylinder and controlling the admission of compressed air to said cylinder; a collar upon the lower end of said rod arranged to move said valve into operative position by said initial limited movement of the piston rod; means for limiting the operative stroke of said piston; means whereby said piston closes said valve at the end of the piston stroke; and a spring for returning said piston rod to its initial position.

7. In a trolley-restoring device, the combination with a trolley-pole and a trolley carried thereby for engagement with a feed wire; of a trolley-restoring member comprising arms pivoted at their lower ends to said pole and provided at their upper ends with a fork having a central groove and arms extending therefrom upon the opposite 125 130

side of the trolley; a bell-crank lever pivoted at its apex and at one end thereof to said pole and said arms of the restoring member, respectively; a piston rod having an upward extension pivotally connected to the other end of said bell-crank lever, and arranged to be given an initial limited movement in one direction by the pressure exerted when said trolley-restoring member engages said feed-wire; a cylinder having a closed upper end and an open lower end; a piston fitting in said cylinder and secured to said piston rod intermediate the ends thereof; a cylindrical valve slidably mounted in the lower end of said cylinder and controlling the admission of compressed air to said cyl-

inder; a collar upon the lower end of said rod arranged to move said valve into operative position by said initial limited movement of the piston rod; means for limiting the operative stroke of said piston; means whereby said piston closes said valve at the end of the piston stroke; and a spring for returning said piston rod to its initial position.

25 In witness whereof, I, hereunto subscribe my name this eleventh day of January A. D., 1910.
